UNITED STATES PATENT OFFICE

173,289

CHESSMAN

Chester D. Vedder, Niskayuna, N. Y.

Application July 20, 1953, Serial No. 26,037

Term of patent 7 years

(Cl. D34—5)

To all whom it may concern:

Be it known that I, Chester D. Vedder, a citizen of the United States, residing in the town of Niskayuna, in the county of Schenectady and State of New York, have invented a new, original, and ornamental Design for a Chessman, of which the following is a specification, reference being had to the accompanying drawing, forming a part hereof.

Fig. 1 is a side elevation view of a chessman, showing my new design; and

Fig. 2 is a plan view thereof.

I claim:

The ornamental design for a chessman, as shown.
